Frank A. Wojcik, Indianapolis, Ind.

Application February 24, 1941, Serial No. 380,380

3 Claims. (Cl. 123—171)

My invention relates to the cooling of air-cooled internal combustion engines of the type employed for the propulsion of airplanes.

An object of my invention is to provide an improved cowling of a streamlined design and provided with shutters adapted to be opened and closed in response to variations in engine temperatures for effectively regulating the flow of cooling air.

The present invention is particularly adapted to an engine of the radial type, and the cowling is provided with a series of shutters operatively connected with an actuating device which is thermostatically controlled for regulating the positions of the shutters in accordance with predetermined engine temperature conditions. The shutters are connected as a unit with the actuating mechanism, and a manual control is also provided whereby the shutters may be manually manipulated independently of the temperature responsive control system.

In the accompanying drawings:

Figure 1 is an elevational view of the cowling; Figure 2 is an enlarged sectional view taken along the line 2—2 of Figure 1;

Figure 3 is an enlarged longitudinal sectional view of the greater part of the cowling;

Figure 4 is a fragmentary perspective view of one of the shutters illustrating one shutter hinge, there being two hinges for each shutter;

Figure 5 is a fragmentary perspective view illustrating a master bearing mounted on the nose section of the crank case and provided with a rotative ring having arm connections with the respective shutters for moving the latter to open and closed positions through rotation of the ring;

Figure 6 is a view taken from the position indicated by line 6—6 of Figure 1 and constitutes a top plan view of the ring, a fragment of which ring is illustrated in Figure 5;

Figure 7 is a sectional view along the line 7—7 of Figure 6;

Figure 8 is an enlarged perspective view illustrating the hydraulic control circuit connected with the ring of Figures 5 and 6, together with the manual control;

Figure 9 is a top plan view of a hydraulic cylinder interposed in the hydraulic circuit for actuating the shutters, with a portion of the cylinder broken away for the sake of clearness;

Figure 10 is a sectional view taken substantially along the line 10—10 of Figure 9;

Figure 11 is a sectional view of a thermostatically controlled valve which automatically opens and closes the hydraulic circuit for actuating the shutters, the thermostat of which valve is preferably located in the engine oil sump;

Figure 12 is a sectional view along the line 12—12 of Figure 11; and

Figure 13 is a view taken from the position indicated by line 13—13 of Figure 11.

In the embodiment selected to illustrate my invention, I make use of an engine crank case 20 of an engine 21 illustrated in dotted lines in Figs. 1 and 3. The engine may be of the conventional radial type and is illustrated as comprising one row or bank of cylinders. The usual crankshaft 22 extends through the crank case 20 for connection with the hub 23 to which the propeller 24 is connected. My improved cowling 25 encloses the engine 21 and the crank case 20, and the cowling tapers noseward and the nose comprises a spinner 26 and a spinner cap 27. Cap 27 is preferably rubber covered.

The forward end of the cowling 25 is riveted to a flange 28 having a flange 29 fitting snugly about the forward end of the crank case 20 and secured thereto by bolts 30. The rear end of the fuselage fits about a band 31 to which the forward end of the fuselage shell 32 is also secured. Both the cowling and the shell 32 may be riveted to the band 31, and the latter is provided with an annular rib 33 for reinforcing purposes.

The cowling 25 is provided with a series of air inlet openings 34 extending longitudinally of the cowling throughout its greater length. To the inner side of the cowling 25 and adjacent each side edge of the openings 34 is secured a reinforcing T-member 35, which members constitute structural reinforcing elements for the cowling as well as the fuselage shell. The cowling as well as the shell 32 may be riveted to the members 35. Each opening 34 is provided with a shutter 36 which may completely close its respective opening as well as to uncover the opening in different degrees, depending upon engine condition. Each shutter 36 is secured to the cowling 25 along one edge margin of the shutter. Fig. 4 best illustrates the manner in which the shutters are hinged. The fragmentary shutter 36 in this view is offset at 37 to provide a flange 38 which extends completely about the perimeter of the shutter, and the flange 38 overlaps the inner face of the cowling 25 completely about its respective opening 34. All the shutters are identical in construction so that the description of one will apply to all.

Fig. 4 illustrates one hinge connected with its respective shutter 36, which hinge includes a hinge part 39 riveted at 40 to the web 41 of the T-member 35. Hinge part 39 is connected with a companion hinge part 42 through the medium of the usual pin 43, and the part 42 is bent to lie snugly against the face 44 of the T-member 35, the inner face of the flange 38 and against the inner face of the shutter 36, to which the hinge part is fixedly secured by rivets 39. Fig. 3 illustrates the relative spacing of the hinges associated with the shutters 36, and the taper of the cowling 25 is such that a straight line drawn through the

axes of the hinges on a shutter will be arranged at an angle of $22\frac{1}{2}^{\circ}$ to the axis of the cowling or shaft 22.

The crank case 20, see Fig. 5, is provided with a circumferential rib 45 upon which is mounted a band 46 which is provided with a flange 47 along one edge and a band 48 along the opposite edge, which flange and band are spaced to provide a bearing race for a ring 49. The band 46 is clamped against the rib 45 through the medium of screws 50 which pass through the band 48 and the band 46 and are threaded into the rib 45. Fig. 5 illustrates one of the screws 50 and Fig. 6 illustrates the spacing of the screws.

Ring 49 rotates on the band 46 and is restrained from lateral shifting by reason of the flange 47 and the band 48. Specifically, the ring comprises two sheet metal flanges 51 arranged face to face and each flange having a right-angled flange 52 bent back upon itself to provide a narrow flange 53 which rides on the band 46. The flanges 51 are connected into a unitary structure through the medium of rivets 54. Flanges 51 are also provided with ears 55 spaced circumferentially of the ring 49. The ears on one flange 51 lie face to face with the ears on the other flange so that each pair of ears constitutes a lug 56, with the number of the lugs equaling the number of shutters 36.

To each shutter 36 is riveted an attaching member 57 and each attaching member is connected with a tubular connecting rod 58 through the medium of a universal joint 59, and each connecting rod 58 has its other end connected with one lug 56 through the medium of a universal joint 60. Figs. 2 and 8 best illustrate the arrangement of the connecting rods. The connecting rods 58 are connected with their respective shutters 36 at the center of pressure of the shutters when the latter are in closed positions. The shutters are opened through rotation of the ring 49, which rotation causes the connecting rods to exert a pull on the shutters and swing the latter to open positions about the axes of their respective hinges.

Means for rotating the ring 49 for opening and closing the shutters 36 comprises a cable 61 having one end connected with a coupling member 62 riveted to the flanges 51, see Fig. 6. The cable passes around a grooved wheel 63 supported by a bracket 64 mounted on the crank case 20 and around a grooved wheel 65 rotatably mounted on a coupling member 66, see Figs. 6, 8 and 10, which coupling member is threadedly connected with one end of a piston rod 67, as in Fig. 10. In Fig. 6, the opposite end of the cable 61 is connected with an eye 68.

A second cable 69 has one end connected with a coupling member 70 riveted to the flanges 51, see Fig. 7, and the cable passes around a grooved wheel 71 carried by a bracket 72 attached to the crank case 20. The cable 69 extends rearwardly of the crank case 20, see Fig. 8, and passes around a grooved wheel 73 carried by a bracket 74 secured to the crank case. From the pulley 13, the cable 69 passes around a grooved wheel 75, another grooved wheel 76 and a grooved wheel 77 which may be rotatably mounted on any suitable support within convenient reach of the attendant, and the wheel is provided with a handle 78 to facilitate rotation thereof. From the grooved wheel 77 the cable 69 passes around a grooved wheel 79 associated with the wheel 76 and both wheels are rotatably carried by a clevis 80 connected with a tension spring 81 also secured to

a bracket 82 which may be fixedly connected with any suitable support on the craft. From the grooved wheel 79 the cable 69 passes around a grooved wheel 83 associated with the wheel 75 and is then connected with a fixed post 84. Wheels 75 and 83 are rotatably carried by a clevis 85 best illustrated in Figs. 8 and 10. The clevis 85 is threadedly connected with the opposite end of the piston rod 67.

Piston rod 67 extends through stuffing boxes 86 at the ends of a cylinder 87 having lugs 88 bolted to the crank case 20. Thus the piston rod 67 slidably extends through the stuffing boxes 86 and reciprocatory motion of the piston rod is converted into rotary motion of the ring 49. Fig. 8 illustrates the shutters 36 in closed positions and rotation of the ring 49 in the direction of the arrow 89 exerts a pull on the connecting rods 58 and simultaneously moves the rods and shutters 36 to the dotted line positions of Fig. 2.

Rotation of the wheel 71 in a counter-clockwise direction when viewing Fig. 8 exerts a pull on the end of the cable attached to the post 84 for moving the piston rod 67 to the positions of Figs. 8 and 10, at which time the ring 49 is rotated for fully closing the shutters 36, since the cable 61 is attached to a fixed eye at one end and to the ring 49 at its other end. Similarly, clockwise rotation of the wheel 71 exerts a pull on the cable 69, particularly the end of the cable attached to the ring 49 for rotating the ring in a clockwise direction when viewing Fig. 8, which rotation of the ring moves the shutters to an open position. Such actuation of the cable 69 causes the piston rod 67 to be shifted to its opposite extreme position, since the cable 61 is attached to the ring 49 and this cable will be pulled by the ring as the ring is rotated by reason of the pull on the cable 69. A piston 90 is mounted on the piston rod 67 inside the cylinder 87, which piston divides the cylinder into chambers 91 and 92 having communication one with the other by reason of a bypass pipe 93 provided with a valve 94 which may be manually adjusted to open and closed positions. When the valve 94 is opened, the piston 90 may move freely inside the cylinder 87 since fluid displaced from one chamber is transferred to the other chamber.

0 Valve 94 is provided with an arm 95 connected with an operating wire 96 slideable in a spiral housing 97, which wire is provided with a knob 98 to facilitate manipulation of the wire, see Fig. 8.

5 The automatic shutter operating mechanism comprises pipes 98 and 99 which respectively communicate with the chambers 91 and 92. These pipes connect with the body 100 of a thermostatically controlled valve 101. The body 100 is provided with a bore 102 within which is rotatably disposed a valve 103 having a shaft 104 fixed thereto and connected with one end of a bimetal spring 105 having its other end attached to a pin 106 carried by a bearing base 107 which 10 may be made secure inside the engine oil sump so as to make the spring 105 responsive to the temperature of the oil in the sump. Bearing base 107 is provided with openings 108 for the reception of bolts (not shown) which may be 15 utilized for anchoring the base.

Valve 103 is provided with two grooves 109 and 110, and the body 100 is provided with ports 111, 112, 113 and 114 which lie in a common plane and in the plane of the grooves 109 and 110. Pipes 75 98 and 99 are attached to the valve body 100.

through the medium of coupling elements 115, and the pipes respectively communicate with the ports 112 and 111.

Fig. 12 illustrates the plug 103 adjusted to a position which locates the groove 110 for placing the ports 111 and 113 into communication. Grooves 109 and 110 are isolated one from the other so that neither groove can have communication with the other. To the valve body 100 is connected pipes 115 and 116 which communicate with an oil sump or reservoir tank 117. An oil pump 118 is interposed in the pipe 115, which oil pump may comprise one of the oil pumps of the engine. Fig. 12 illustrates the pipe 115 as being connected with the body 100 through the medium of a coupling element 119, and the pipe communicates with the port 114. Similarly, the pipe 116 is attached to the body 100 through the medium of a coupling element 120, and the pipe communicates with the port 113.

With the valve 103 positioned according to Fig. 12, oil in the pipe and pump system will be forced into the port 114, through the groove 109 and into the pipe 98 which forces the piston 90 of Fig. 10 to the position shown therein. At the same time, pipe 99 communicates with the port 111 and with the pipe 116 through the medium of the groove 110 and the port 113 so that oil from the chamber 92 in the piston may be returned to the reservoir 117. The valve 103 is controlled through the action of the bimetal spring 105. Rotation of the valve in a clockwise direction when viewing Fig. 12 brings the port 111, the groove 109 and the port 114 into communication, and the ports 112 and 113 are brought into communication one with the other through the medium of the groove 110. Accordingly, the oil will be forced into the chamber 92 in the cylinder 81 for moving piston 90 to the left, as when viewing Fig. 10.

In the present invention, the cowling 25 is tapered in such manner as to eliminate air resistance, and the engine nose section length is slightly greater than the conventional engine nose section, this difference providing the unobstructed depth needed for the inward and backward action of the shutters. The cowling is devoid of abrupt obstructions immediately in the rear of the propeller blades.

The shutter action is regulated through the medium of the oil temperature of the engine. The automatic control is so arranged that there is no fixed relation between the engine temperature and the amount of shutter opening. Such an arrangement provides for the ever-changing atmospheric temperature.

The shutters are of elongated contour with respect to the line of flight so that the hinge lines are set at small angles to the line of flight. This arrangement permits the incoming air to enter the cowling practically undisturbed, thus keeping the surplus cooling air from disturbing the air flow around the nose of the cowling. The number of shutter openings in the cowling is equal to the number of cylinders in the engine for which a particular cowling is designed. This arrangement gives each cylinder an individual center opening.

Having thus described certain embodiments of my invention in detail, it is, of course, understood that I do not desire to limit the scope thereof to the exact details set forth except insofar as those details may be defined in the appended claims.

I claim:

1. In combination, a plurality of shutters circularly disposed and each pivotally mounted upon a generally longitudinal axis and spaced one from the other, a crankcase, said crankcase being elongated to provide the unobstructed space required by the inward and backward action of the shutters, a circumferential rib integrally mounted around said crankcase, a ring, said ring being rotatably mounted around said circumferential rib, connecting rods between said shutters and said ring for simultaneously advancing the shutters when the ring is rotated in one direction and for simultaneously receding the shutters when the ring is rotated in the opposite direction, a servo-motor, a plurality of cables connecting said ring and said servo-motor for converting the reciprocating action of the servo-motor to rotative action of the ring, a fluid circuit, pipes operatively connecting fluid circuit with said servo-motor, a valve interposed in said fluid circuit for reversing the action of the servo-motor, an oil sump, and a temperature responsive element located in said oil sump and operatively connected with said valve for actuating the latter.
2. In combination, a plurality of shutters circularly disposed and each pivotally mounted upon a generally longitudinal axis, a crankcase, said crankcase being elongated to provide the unobstructed depth required by the inward and backward action of the shutters, a circumferential rib integrally mounted around said crankcase, a ring, said ring being rotatably mounted around said circumferential rib, connecting rods between said shutters and said ring for advancing the shutters when the ring is rotated in one direction and for receding the shutters when the ring is rotated in the opposite direction, a servo-motor, said servo-motor having a by pass valve providing for actuating the servo-motor manually, a plurality of cables connecting said ring and said servo-motor for converting the reciprocating action of the servo-motor to rotative action of the ring, a fluid circuit, pipes operatively connecting fluid circuit with said servo-motor, a valve interposed in said fluid circuit for reversing the action of the servo-motor, an oil sump, a temperature responsive element located in said oil sump and operatively connected with said valve for actuating the latter and a manual control operatively connected with said servo-motor for advancing and receding said shutters independently of the oil temperature in said oil sump.
3. In combination, a plurality of shutters circularly disposed and each pivotally mounted upon a generally longitudinal axis to swing towards and away from the axis of a circle, a crankcase, said crankcase being elongated to provide the unobstructed depth required by the inward and backward action of the shutters, a ring, said ring being rotatably mounted around said crankcase, connecting rods between said shutters and said ring for advancing the shutters when the ring is rotated in one direction and for receding the shutters when the ring is rotated in the opposite direction, and means manually operating said ring, said means including a plurality of cables connected at one end to said ring and at the other end to a wheel.

FRANK A. WOJCIK.
